PORTRABLE PICNIC TABLE

Martin Krone, 60 E. 42nd St., New York, N.Y.

Filed Jan. 4, 1963, Ser. No. 73,047

Term of patent 14 years

(Cl. D33—14)

FIG. 1

FIG. 2

FIG. 3

FIG. 4

I claim:

The ornamental design for a portable picnic table, substantially as shown.
